UNITED STATES PATENT OFFICE.

CLAES RYDEN, OF PROVIDENCE, RHODE ISLAND, ASSIGNOR TO UNIVERSAL WINDING COMPANY, OF PORTLAND, MAINE, A CORPORATION OF MAINE.

REEL OR SWIFT.

1,055,419.

Specification of Letters Patent.

Patented Mar. 11, 1913.

Original application filed August 17, 1910, Serial No. 577,597. Divided and this application filed December 7, 1910. Serial No. 596,073.

To all whom it may concern:

Be it known that I, CLAES RYDEN, a citizen of the United States, residing at Providence, in the county of Providence and State 5 of Rhode Island, have invented certain new and useful Improvements in Reels or Swifts, of which the following is a specification.

My invention relates to improvements in reels, swifts or similar devices used for holding skeins in unwinding the same to deliver 10 the yarn to winding or other textile machines.

My improved swift or reel is particularly adapted for use where the skein-holder is 15 rotated to unwind the yarn and provided with means to control its rotation and automatically regulate the tension of the delivering yarn.

The object of my improvement is to provide 20 a more effective holding surface on the swift or reel, so that the latter will be positively rotated by the draft on the yarn, and even when the skein is nearly run off the last few coils will still cling to the reel to 25 continue its rotation as required to maintain the tension on the yarn.

The invention is fully set forth in the following specification, illustrated by the accompanying drawings, in which:—

30 Figure 1 is a view of a winding machine showing a skein-unwinding device in which my improved form of reel is employed; Fig. 2, an isometric projection of the reel or "runner" in its preferred form; Fig. 3, 35 a similar view of another form of skein-holder or "swift".

In Fig. 1 I have shown a usual form of winding machine designated A with a skein-unwinding device applied thereto similar 40 to that described in my pending application, Serial No. 577,597, filed August 17th, 1910, from which the present case is divided. The winding machine A has horizontally projecting spindles c on which the bobbins b 45 are wound and the thread or yarn is traversed by a thread-guide d reciprocating opposite the spindle and feeding progressively outward to build up the conical layers of winding.

50 As described in detail in my previous application above referred to, the skein-unwinding device here shown is carried on the A-shaped brackets B which surmount the

top of the frame of the machine. The brackets B support horizontal rods or bars e and 55 j and on the bar e are mounted arms E which have bearings for the reels or swifts. I have here shown the device arranged for reels, or "runners" as they are generally termed, similar to that illustrated in Fig. 60 2. The upper runner R rotates on a stud r held in a bearing on the arm E and the lower runner R' is rotatably supported on an arm F hinged on the bracket G. The bracket G is mounted on a standard h extending upwardly from a bracket H fastened to the rod j. The skein S is stretched over the two runners R and R' and, preferably, the arm F is held down by suitable frictional tension means to draw the 65 coils of the skein taut. The draft on the yarn as it is taken up by the winding operation causes the two runners R and R' to rotate and its delivery from the skein is regulated by controlling the rotation of the 70 larger runner R. The controlling means for the runner R is shown and described in detail in the application before referred to and therefore requires no specific description herein. In general, the mechanism 75 consists of a spring take-up arm t operated by the draft on the yarn to apply a rotative impulse to the runner R in starting the unwinding of the skein, or to overcome any hindering tendency to the delivery of the 80 yarn caused by snarling or tangling of the coils. The arm t also acts as a brake actuating device to regulate the speed of rotation of the runner and thereby control the 85 tension on the yarn. The arm t is preferably 90 constructed of flat spring steel and is pivoted or fulcrumed on the stud r on which the runner R rotates. At its outer extremity it carries a guide or "pig-tail" t' through which the yarn y draws from the 95 skein. From the guide t' the yarn leads down through another guide z supported at the end of a secondary spring arm z', which provides an auxiliary yielding element, and thence to the traverse thread-guide d. A 100 V-shaped truss-like extension t² is secured to the upper end of the arm t to serve as a stiffening means, so that the arm will not bend throughout its whole length, and to this extension is secured the rotation controlling means for the runner R. This con- 105

sists of a flexible brake-band *s* arranged to surround and frictionally engage the periphery of a brake-drum *o* which is formed on the hub of the runner *R*. One end of the band *s* is fastened at *t*² to an offset finger, not here shown, on the extension *t*² and to its opposite extremity is secured a coiled spring *u*. The other end of the spring *u* is secured by a clamp *v* to the inclined portion *t*⁴ of the extension *t*². The clamp *v* is fastened by a set screw *v*' which provides for adjusting the clamp along the incline *t*⁴ to vary the tension of the spring *u* and also the extent of contact of the brake-band with the periphery of the drum *o*. A flat, spring-tempered arm *w* extends from the end of the arm *t* downward along the arm *E* with its extremity held in a slot at the end of the rod *x*. The rod *x* is adjustable longitudinally in a lug *e*⁵ on the arm *E* and held by a set screw *x*'. By sliding the rod *x* in the lug *e*⁵ the spring *w* may be engaged at different points along its length to vary the effect of its spring action on the arm *t*.

Referring to Fig. 2 the reel or runner *R* is constructed with a hub *2* formed with end flanges from which project two series of wire spokes *3* supporting the two parallel, annular rims *4* and *5*. Each pair of spokes is formed of one length of wire extending radially outward from one end of the hub *2*, across the rims *4* and *5* and back into the other end of the hub. The wire is doubled back in loops to impinge upon the rims *4* and *5* and extends across in the bars *6* to bridge the space between the rims. In this way two flanges are provided on the opposite sides of the reel adapted to retain the coils of the skein in position on its periphery. Reels of this general character are well known and have been previously used in the art, but for the purpose herein intended, when the skein is simply held on the cross-bars *6* the contact of the coils of yarn with the reel is not always sufficient to rotate the reel positively. In other words, where there is only a contact of the skein on the relatively narrow cross-bars the coils are liable to slip and slide around the reel when the inertia of the latter must be overcome or when the reel is restrained from free rotation by the tension controlling devices. To guard against this condition and provide a more efficient holding surface for the skein I apply a band *8* of felt, or other rough-surfaced fabric, leather or similar material, stretched around the cross-bars *6* as shown particularly in Fig. 2. This gives a continuous, peripheral, gripping surface around the circumference of the reel and effects a frictional engagement between the skein and the band *8* which prevents the coils from slipping. Even when the skein has nearly run off and there are but two or three coils remaining, these few coils will cling to the

surface of the band *8* and rotate the reel to effect its proper control through the tension or brake devices. In Fig. 1 I have shown the peripheral band *8* applied to the upper reel or runner *R* only, but if desired a similar band might be applied to the other runner *R'*. It is not absolutely necessary, however, for the lower idler runner *R'* to be rotated constantly with the movement of the skein. The braking and tension-controlling devices coact with the upper runner *R*, as previously described, and therefore this runner must be driven positively by the draft on the yarn, the other runner being driven as an idler. It has been demonstrated that the friction surface of the band *8* will insure positive rotation even down to the last few coils of yarn wrapped around the runners.

The operation of the whole device is as follows: The skein *S* is stretched over the runners *R* and *R'* and the arm *F* pressed downward to draw the coils of yarn taut. The friction bearing of the arm *F* on its bracket *G* maintains the arm in its adjusted position and the yarn *y* is led from the upper runner through the guide *t'* and thence down through the auxiliary guide *z* to the thread-guide *d*. When the machine is started the runners *R* and *R'* are inert and the sudden draft on the yarn is liable to break or strain the material before the runners can be started to rotate unless some means is provided to overcome the inertia. With the arrangement shown in Fig. 1 the first quick draft on the yarn pulls the arm *t* bodily downward and the latter acts through the brake-band *s* to initiate the rotation of the runner *R* as follows: The movement of the arm *t* exerts a pull on the end of the band *s* against the resistance of the spring *u* and tightens the band around the brake-drum *o*. The spring *u* is adjusted to give a frictional contact of the band on the drum sufficient to rotate the latter when the band is moved circumferentially around its axis and thereby the runner *R* is rotated to start the unwinding of the yarn. After the inertia of the runners has been overcome by the impulse exerted through the movement of the arm *t* the draft on the yarn is sufficient to keep the runners turning and the arm *t* returns to its normal position under action of the spring extension *w*. The brake-band *s* normally has a contact with the periphery of the drum *o* sufficient to apply a slight braking tendency so that the runners will not gain impetus and run ahead of the draft on the yarn. When a snarl or tangle occurs in the skein, tending to impede the rotation of the runners, the arm *t* will be drawn downward under influence of the increased tension on the yarn and will act as above explained to assist in the rotation of the runners. In this way the rotation of the runners is controlled and automatically regulated by the tension

of draft on the yarn and the skein can be unwound to deliver the yarn without break or hindrance.

The improved reel or runner shown and described is particularly adapted for use in unwinding skeins of silk, or other smooth and slippery materials, and is especially effective for controlling the delivering yarn or thread down to the last coil in the skein. Heretofore, with the usual form of reel, the last coils of the skein would slip around the circumference and unwind without tension and were apt to fall down and become tangled in the machine. Furthermore, unless a uniform tension is maintained up to the end of delivery the layers of the bobbin will be poorly wound, becoming loose or sloughing off, and thereby causing waste of material and loss of time.

In Fig. 3 I have shown another form of reel, generally called a "swift", used for holding the skein without the employment of an auxiliary runner. This form of reel is intended for use with controlling mechanism similar to that shown and described in my application for patent, Serial No. 524,196, filed October 23rd, 1909, and in general operates in the same manner as the reel R, previously described. In this form of reel there are two sets of spokes 9 radiating from the opposite ends of the hub 10 and their outer ends are connected by the twisted loops of cord 11. My improvement is applied by stretching the fabric band 12 around over the cords 11 and the band takes a polygonal shape with the skein conforming thereto. As with the previously described form of reel, the rough fabric gives a gripping surface to which the coils of the skein cling so that the swift can be rotated by the draft on the yarn.

Having now described my invention in

full and set forth the manner in which it is made use of for attaining the improved result shown, what I claim is:—

45

1. An improved reel or runner for skein-unwinding devices comprising a hub, two series of spokes radiating therefrom in pairs, cross members connecting the ends of each pair of spokes and a fabric band 50 stretched around the cross members to provide a friction surface for the yarn.

2. In an improved reel or swift for skein-unwinding devices, the combination with the hub and spokes, of a peripheral band of 55 frictional material extending around the swift in polygonal form adjacent the ends of the spokes to provide a holding surface for the coils of yarn.

3. An improved reel for holding skeins 60 of textile material in unwinding the same, comprising a wheel-shaped framework and a rough-surfaced band extending circumferentially around the framework to provide a friction holding surface for the coils of 65 yarn.

4. As a new article of manufacture, a reel or swift, for holding skeins of textile material in skein unwinding devices, having its 70 circumference surrounded by a continuous band of rough-surfaced material substantially as shown and described.

5. A reel or swift, for holding skeins of 75 yarn or other textiles in skein unwinding devices, having a roughened peripheral surface adapted to frictionally engage the coils of yarn to prevent them from slipping around the reel.

In testimony whereof I affix my signature in presence of two witnesses.

CLAES RYDEN.
